(57) **CLAIM**

The ornamental design for a clip container, as shown and described.

DESCRIPTION

FIG. 1 is a perspective view of the clip container showing my new design;

FIG. 2 is a front view thereof;

FIG. 3 is a rear view thereof;

FIG. 4 is a left side view thereof;

FIG. 5 is a right side view thereof;

FIG. 6 is a top view thereof;

FIG. 7 is a bottom view thereof; and,

FIG. 8 is an operational perspective view of the clip container that contains multiple paper clips inside, wherein some paper clips are magnetically attracted by a cover of the clip container; wherein, the broken lines are shown for illustrative purposes only and form no part of the claimed design.
